UNITED STATES PATENT OFFICE.

WILLIAM F. LAUTENSCHLAGER, OF CINCINNATI, OHIO.

SEWING MACHINE.

Application filed July 26, 1919. Serial No. 313,602.

To all whom it may concern:

Be it known that I, WILLIAM F. LAUTENSCHLAGER, a citizen of the United States, residing at Cincinnati, in the county of 5 Hamilton and State of Ohio, have invented certain new and useful Improvements in Sewing Machines, of which the following is a specification.

In sewing machines as ordinarily constructed, in which a loop-taker operates to take the loop at the side of the line of feed, especially in so-called lock-stitch sewing machines, the needle is so placed that its eye continuously extends crosswise of the 10 line of feed of the material, that is, crosswise of the seam, the loop of the thread passing through the material while arranged crosswise of the seam, so as to develop a loop at the side of the seam, below the material, which loop is arranged to be taken a 15 loop-taker at the side of the seam toward which the loop has been developed. The result of this usual arrangement of the devices is a seam, the surface stretches of 20 which extend slantingly with relation to the line of the seam. I have found it very desirable, for certain classes of work, to employ a seam in which the exposed stretches or sections of thread are arranged 25 lengthwise of the seam, so as to make a line coincident with the line of the seam.

It is the object of my invention to lay the exposed stretches or section of the seam in the line of the seam and to develop the loops 30 at the side of the seam; further, to provide means for accomplishing such object; further, to provide means whereby the eye of the needle, which is at the penetrating end of the needle, is arranged lengthwise of 35 the seam when penetrating the material, and is turned at the reverse face of the material for extending crosswise of the line of the seam in order to present the loop developed in proper direction to a loop-taker at the 40 side of the needle; further, to provide means whereby to impart a spiral movement to the needle; further, to provide means for reciprocating the needle-bar lengthwise and for locating the needle-bar so as to present 45 the thread-eye of the needle in different directions at different points in the path of the needle-eye; further, to provide means in connection with the loop-taker for recip-

rocating and rotating the needle-bar in order to present the eye of the needle in a 55 different direction to the loop-taker than to the line of the seam when the thread-eye is passing through the material; and, further, to provide adjusting means whereby to adjust the operative relation between 60 the thread-eye of the needle and the loop-taker.

The invention will be further readily understood from the following description and claims, and from the drawings, in 65 which latter:

Fig. 1 is a front elevation of a sewing machine embodying my invention.

Fig. 2 is a front elevation of the head-end of the same, partly broken away. 70

Fig. 3 is a head-end elevation of the same, partly broken away.

Fig. 4 is a similar view with the cover of the head removed, and with the lower part of the mechanism taken in cross-section on 75 the line 4—4 of Fig. 2.

Fig. 5 is a detail in cross-section on the line 5—5 of Fig. 4.

Fig. 6 is a head-end elevation of the same.

Fig. 7 is a plan view of the mechanism 80 in the bed of the machine, the table of the machine being partly broken away for exposure of the parts.

Fig. 8 is a view similar to Fig. 4, with the needle-bar shown in different relation. 85

Fig. 9 is a perspective view of the guide for the needle-bar.

Fig. 10 is a similar view of a modification of the same. 90

Fig. 11 is a plan view showing the face side of the old-style diagonal stitching at 20.

Fig. 12 is a plan view of stitching made under my invention. 95

Fig. 13 is a head-end elevation of portions of the mechanism, partly broken away, and partly in cross-section in the axial plane of the needle, showing the thread-eye of the needle extending in the line of the 100 seam, and in the plane of the material.

Fig. 14 is a similar view, the thread-eye of the needle extending in the line of the seam, and having just penetrated the material. 105

Fig. 15 is a similar view, showing the

needle at the beginning of its up-stroke, with its eye extending crosswise of the line of the seam and with the loop just developed and the entering end of the loop-taker being received into the loop.

Fig. 16 is a similar view showing the needle at the beginning of its retractive rotation, with its thread-eye extending slantingly crosswise of the line of the seam and with the loop further developed and the loop penetrating part of the loop-taker in position of further advancement.

Fig. 17 is a similar view, showing the completed stitch with the thread-eye of the needle extending in the line of the seam.

Fig. 18 is a detail of the needle-securing means, taken in the axial plane of the needle; and,

Fig. 19 is a cross-section of the same, taken on the line 19—19 of Fig. 18.

The frame of the machine is represented at 21, and is shown as comprising a table 22, a pedestal 23, and an arm 24 extending above the table, the arm having the head 25 at its outer end. A drive-shaft 29 is journaled in suitable bearings in the frame, is suitably driven, and is arranged to rotate a shaft 30 under the table of the machine by a suitable means, as by connecting links 31, 32, having bearings about cranks 33, 34, of the shaft 29 and cranks 35, 36, of the shaft 30.

A crank-disk 41 is fixed to the shaft 29 and is provided with a crank-pin 42, about which a connecting link 43 has a bearing 44 at one end thereof, the other end of the connecting link having a bearing 45 about the journal of a suitable reciprocating bearing-piece 46, suitably guided, as by having a roller 47 thereon received in a guide-slot 48 in the head and having a bearing 49 about a needle-bar 51. (See Figs. 4, 5 and 6).

The needle-bar 51 is secured in lengthwise relation to the bearing 49, as by means of clamps 52, 53, clamped at the respective ends of the bearing 49 about the needle-bar, for instance, by means of clamp-screws 54. These clamps are arranged to be adjustably positioned and clamped lengthwise of the needle-bar for adjusting the position in the length of the needle-bar at which the bearing 49 is located, thereby adjusting the position of the path of lengthwise reciprocation of the needle-bar, for adjustment of the same for different lengths and positions of needles.

The needle-bar is provided with a suitable socket 57, in which a needle 58 is received and secured by means, for instance, of a set-screw 59. The relation between the needle and the needle-bar may be fixed, as by providing the shank of the needle with a flattened side 60 received against the flattened wall 61 of the

needle-socket in the needle-bar, although positioning means of this character may be omitted. (See Figs. 18, 19).

The machine is exemplified as provided with a usual take-up lever 65 for the thread, operated in desirable or usual manner, and is also provided with usual thread guiding and tensioning means of desirable or suitable construction and function.

Suitable presser means are also provided, exemplified as a presser-roll 67, rotatable on an arm 68, extending from a suitable presser-post 69, suitably operated. The presser-roll acts in connection with suitable feeding means, for instance, a feed-bar 71, suitably operated to feed the material in any usual manner. The material is shown as superposed layers 73, 74, and may be textile or fibrous material, such as cloth, leather or canvas, or other desirable material.

The feed-bar is instanced as provided with feeding teeth, and as located on a lever 76, pivoted on a pivot 77 of an arm 78, extending upwardly from a rocker-rod 79, rockable on trunnion-screws 80, adjustable in the frame, and further pivoted by means of a pivot 81 to an arm 82, of a rocker-rod 83, rockable on trunnion-screws 84 adjustable in the frame, the pivot 81 moving in a suitable slot 85 in the lever. (See Fig. 7.) The rocker-rod 83 has a forked-arm 86 secured thereto, the fork of the arm being received about a cam 87 fixed to the shaft 30, for rocking the forked-arm up and down and thereby moving the feed-bar up and down. Forward and back movement is imparted to the feed-bar by its connection with the rocker-rod 79, the latter having an upwardly extending arm 90, with which a link 91 is articulated at 92, the link 91 being reciprocated lengthwise in suitable manner.

The effect of the arrangement of parts is to raise the feed-bar into contact with the lower face of the material, to move the feed-bar in a right line away from the operator to feed the material, to cause the feed-bar to descend at the end of the feeding movement, and to return the feed-bar to initial position by a movement toward the operator. The feed-bar operates in a slot 93 in a throat-plate 94. Suitable means are also provided for adjusting the lengths of steps of feed in usual manner. The feeding movement of the feed-bar is lengthwise of the feed-bar, as indicated by the arrow *a* in Fig. 7.

The needle has a thread-eye 101 at its penetrating end, and is provided with a long groove 102 above one end of the thread-eye, this groove being arranged to receive the supply-limb 103 of the thread. (See Figs. 13-17). The needle is also provided with a short groove 104 at the other end of its thread-eye, this latter groove being ar-

ranged to receive the seam-limb 105 of the thread, the bight 106 of the loop formed about the needle, when the latter is in down position, being in the thread-eye. The needle 5 passes through a hole 107 in the throat-plate.

The supply-limb is received through a hole 110 in the needle-bar, this hole being located above and in the vertical plane in 10 which the grooves of the needle are located when the needle is properly attached to the needle-bar. (See Figs. 13-19). This hole is shown in a lug 111 of the needle-bar, above which there is a recess 112 in 15 the needle-bar. A thread-pressing finger 114 extends crosswise of the needle-bar below the hole 110 and is arranged to press up- 20 on the thread for pressing the thread between it and a thread-bearing face 115 on the needle-bar. This thread-pressing finger 25 is shown on a spring-plate 116 fixed to the needle-bar by means of a clamp-screw 117.

The object of this thread-pressing finger 30 is to exert tension upon the supply-stretch of the thread at a point between the guiding hole located in the plane of the grooves of the needle and the thread-eye of the needle, in order to aid in the positioning of 35 said supply-limb lengthwise with relation to the material in the passage of the needle into, and especially out of the material.

Means are provided for rotating the 40 needle-bar, exemplified as a rotative reciprocation of the needle-bar. These means are exemplified as consisting of a guide, shown as a tube 121, in which the needle-bar has movement. The tube is provided with a 45 guide, shown as a slot 122, which includes a spiral portion 123. The guide preferably has an upper end portion 124 and a lower end portion 125, which are parallel with the axis of the needle-bar. These parallel portions or straight portions of the guide or 50 slot are located at different angular positions about the needlebar. The needle-bar is provided with a coacting member which coacts with the walls of the slot, exemplified as a screw 127 threaded into the needle-bar 55 and having a roller 128 thereabout.

The tube is preferably secured with 60 relation to the frame of the machine, and is exemplified as provided with a threaded portion 131, which is adjustable in a threaded bearing 132 in the head of the machine. The tube may be provided with a polygonal head 133 by means of which it may be turned in its bearing. A jam-nut 134 is received about the threaded portion, and 65 after adjustment of the tube in its bearing, is arranged to be clamped against the bearing, so as to clamp the tube in adjusted positions.

If desired, a guide having one wall may 70 be employed in place of the two-walled

groove. When employing a one-wall guide, a spring acting rotatively on the needle-bar may urge the coacting part on the needle-bar against the one-walled guide.

In the sewing machine exemplified, the 75 loop-taker is at the right of the path of the needle. My invention is adapted for sewing machines having a loop-taker at the left of the path of the needle, by employing a spiral guide in which the spirality is opposite to the spirality shown in the principal figures of the drawing. Thus, referring to Fig. 10, the tube 141 is provided with a groove 142 having a spiral portion 143 and straight end portions 144, 145, the spiral 80 portion 143 being reversed to the spiral portion 123.

Suitable loop-taking means are provided. These may be in the form of an ordinary reciprocating loop-taker or shuttle, but I 85 prefer to employ a rotary loop-taker 151 comprising a loop-penetrating hook 152, and a bobbin-case 153, in which a suitable thread-bobbin 154 may be received, for supplying a thread 155, which may represent the locking 90 thread of the stitch. (See Figs. 7, and 13-17). The present exemplification is of a locking stitch sewing machine, although it is obvious that my invention may be employed in other relations and with other characters 95 of sewing machines than that herein shown and described.

The loop-taker is arranged to be fixed to a shaft 158 journaled in a bearing 159 of the frame and having a bevel-pinion 160 secured 100 thereto. A bevel-pinion 161, secured to a shaft 162 by a set-screw 163, meshes with the bevel-pinion 160. The shaft 162 is journaled in bearings 164 of the frame, and has a pinion 165 fixed thereto. A gear 166 on the shaft 105 30 meshes with the pinion 165 for driving the same. The meshing relation between the pinions 160 and 161 may be adjusted by loosening the set-screw 163, placing pinion 161 in different meshing relation 110 with the pinion 160, and again securing the pinion 161 to said shaft by tightening said screw.

In operation, the needle-bar is reciprocated lengthwise by means of the crank-disk 41 115 and connecting-link 43 articulated with the bearing 49. During such lengthwise reciprocation, the coacting member on the needle-bar follows the guide 122, causing rotative reciprocation of the needle-bar in one direction on the down-stroke of the needle-bar, and in opposite direction on the up-stroke of the needle-bar, the coacting member being, in the present instance, guided by the walls of the slot 122. When the needle-bar is 120 positioned so that the thread-eye of the needle is above the plane of the material, the thread-eye of the needle preferably extends lengthwise of the line of the feed. This is 125 the relation of the thread-eye while laying 130

the exposed stretch of the switch. (See Figs. 13 and 14).

The relation of the thread-eye, while it is in the material, is shown in Fig. 13, the 5 thread-eye extending lengthwise of the seam 167 or line of feed when the thread-eye is in the material. When the thread-eye has just passed through the material it still preferably extends in the line of the stitch or line 10 of the seam, as exemplified in Fig. 14. When so arranged, the coacting member on the needle-bar is just about to enter the spiral portion 123 of the guiding groove. The needle now continues its penetration through 15 the material, its short groove preferably penetrating the material prior to the beginning of a turning of the needle, induced in the present exemplification by coaction of the coacting member with the spiral guide. 20 During the further penetration of the material by the needle, after the passage of the short groove through the material, the seam-limb 105 of the loop is at the outside of the cylinder of the needle, being pressed by the 25 outer peripheral wall of the needle into the material. The friction of the material upon this seam-limb holds the seam-end of said seam-limb in definite relation to the previously formed part of the seam, for laying 30 the exposed section of the stitch being formed in the line of the direction of feed or direction of the seam, and maintaining such laid relation during rotation of the needle.

The supply-limb is, however, located in 35 the long groove of the needle and turns with the needle. The turning of the needle arranges the thread-eye thereof crosswise of the line of feed, so that, when the needle has penetrated the material to its limit of movement, the thread-eye will be arranged so as to extend at substantial right angles to the line of the seam or line of the feed.

The loop-taker is arranged at the side of the vertical plane in which the line of feed 45 extends, the loop-penetrating part of hook 152 having a path of rotation close to the side of the needle, for penetrating the loop developed at the bight-end of the seam limb when lengthwise retractive movement of the 50 needle begins, as exemplified in Fig. 15. The loop-taker is preferably provided with a usual needle-guard 168, exemplified as a protrusion thereon. The needle is arranged to impinge this protrusion when in down position, so as to prevent bending or breaking of the needle. The crosswise relation of the 55 thread-eye of the needle is preferably maintained during movement in the lower part of its reciprocating path, and is exemplified 60 as controlled by the lower straight end 125 of the slot 122.

When the direction of lengthwise movement of the needle-bar is reversed, the supply-stretch 103 of the thread, being located 65 in the long groove, has a tendency to

move with the needle. The seam-end of the seam-limb of the thread is, however, held in down position by the friction of the material against it. The thread-eye rising, causes development of the loop for the loop-taker, the loop being projected crosswise of the line of feeding movement and into the path of the rotary loop-penetrating part or hook.

As soon, therefore, as the loop for the 75 loop-taker begins to develop, the loop-penetrating part enters the loop, as exemplified in Fig. 15. Preferably when this penetration has been had, the coacting member on the needle-bar re-enters the spiral portion 80 of the guide for causing beginning of the reverse rotary movement of the needle-bar for returning the needle-bar to its initial relation. The development of the loop continues for supplying a greater stretch of 85 loose thread in order to permit further penetration of the loop, as indicated in Fig. 16.

The loop is then finished, in usual manner, by rotation of the loop-taker, for placing the exposed thread about the bobbin thread, in the present exemplification, for developing the lock or knot of the stitch. When the loop has been fully developed, the take-up begins to act to tighten the 90 thread. The needle also continues its ascent, and, when in fully raised position, the thread is stretched between the thread-pressing finger 114 and the stitch just formed, the thread passing through the eye of the 95 needle, which, in the present exemplification has again been arranged lengthwise of the feed by the re-entrance of the roller on the needle-bar into the upper portion of the guiding slot. (See Fig. 17).

The thread-pressing finger 114 aids in maintaining the relation of the supply-limb of the thread to the long groove in the needle and aids in causing coincident movement of the supply-limb with the lengthwise movement of the needle. It is especially useful when sewing oily goods, or goods which have been previously connected by a rubber cement, or when employing 100 an oiled thread.

The point in the periphery of the feed-wheel where it contacts the material is preferably closely adjacent to the path of the needle so as to act as a guide for the needle 105 when entering the material.

It is desirable that the rotative reciprocation of the needle be adjusted with relation to its lengthwise reciprocation and to the movement of the loop-penetrating part, so that the development of the loop may be 110 adjusted with relation to the movement or rotation of the loop-taker.

For accomplishing this, the guide for the rotative movement of the needle-bar, that is to say, the tube 121 is, in the present in- 115

stance, adjustable lengthwise in its bearing 132, for instance, by rotating the tube in its bearing, whereby the lengthwise relation of the tube to its bearing and to the needle-
5 bar, as well as the loop-taker, is affected. The thread between the tube and its bearing is preferably a fine low-pitch thread, so that delicate lengthwise adjustments may be made. The rotative adjustment of the
10 guide also adjusts the angular positions of the thread-eye of the needle at its limits of movement.

If desired, the needle-bar may also be adjusted lengthwise with relation to the tube, 15 as by unclamping the clamp-rings 52, 53, by loosening the clamp-screws 54, moving the needle-bar lengthwise in the bearing 49, and again clamping said clamp-rings in place about the needle-bar.

20 My invention provides simple and convenient means whereby the exposed stretches of the seam may be laid in the true line of the seam or line of the feed, and laterally extending loops may be developed for the reception of a loop-taker operating at the side of the line of feed. It is also readily adapted for insertion in existing machines not now provided with my invention.

25 Having thus fully described my invention, what I claim as new and desire to secure by Letters Patent, is:

1. In a sewing machine, the combination 30 of a reciprocating needle-bar above the plane of the material, feeding means for the material, a loop-taker below the plane of the material, and means whereby to position the eye of a needle operated by said bar lengthwise of the line of feed of the material when
35 said eye is in the material and to position said eye crosswise of said line of feed when said eye is adjacent to said loop-taker.

2. In a sewing machine, the combination 40 of a reciprocating needle-bar above the plane of the material, feeding means for the material, a loop-taker having a loop-taking part below the plane of the material, means whereby to position the eye of a needle operated by said bar lengthwise of the line of
45 feed of the material when said eye is passing through the material and to position said eye crosswise of said line of feed when said eye is adjacent to said loop-taker, and means for adjusting the position of said eye with relation to said loop-taking part of
50 said loop-taker.

3. In a sewing machine, the combination 55 of a needle-bar above the plane of the material, feeding means for the material, a loop-taker having a loop-taking part below the plane of the material, and a tube above the plane of the material in which said needle-bar reciprocates lengthwise, said tube provided with a helical slot, and said needle-bar provided with guiding means for said

slot, said helical slot and said guiding means arranged in coactive relation during the sewing movements of said needle-bar, whereby a needle operating with said needle-bar is arranged to have its eye extending lengthwise of the line of the seam while passing through the material from above toward said loop-taker and crosswise of said line when below the plane of the material in adjacency to said loop-taking part for presenting the thread-loop transversely of the line of the seam to said loop-taking part.

4. In a sewing machine, the combination 60 of a material-supporting surface, feeding means for the material, a loop-taker below said material-supporting surface, a needle having a thread-eye adjacent its piercing end, and means located above said material-supporting surface for reciprocating and rotating said needle to position said thread-eye lengthwise of the line of feed of said feeding means while said thread-eye is approaching said material-supporting surface from above for piercing the material, and to position said thread-eye crosswise of said
65 line of feed below the material after it has pierced the material for coaction with said loop-taker.

5. In a sewing machine, the combination 70 of a needle-bar above the plane of the material, a needle arranged to be received thereby, said needle having a thread-eye at its piercing end normally parallel with the line of the seam being formed, a long groove at the side thereof normally opening in the direction of the line of the seam for the supply-limb of the thread, a guiding means for said supply-limb, friction means for said supply-limb, said guiding means and said friction means located in that plane parallel 75 with the needle in which said long groove and the longitudinal axis of the needle are located, said guiding means and said friction means located adjacent the upper end of said long groove, and means for combinedly moving said needle-bar, said guiding means and said friction means lengthwise of said needle-bar and about the longitudinal axis of said needle-bar.

6. In a sewing machine, the combination 80 of a needle-bar above the plane of the material, a needle arranged to be received thereby, said needle having a thread-eye at its piercing end normally parallel with the line of the seam being formed, a long groove at one side thereof for the supply-limb of the thread and a short groove at the other side thereof for the seam limb of the thread, said grooves coacting with said thread-eye, said
85 grooves normally opening in the direction of the line of the seam, friction means for said supply-limb adjacent the end of said long groove distanced from said thread-eye, said friction means located in that plane parallel with the needle in which said long
90

groove and the longitudinal axis of the needle are located, and means for combinedly moving said needle-bar and said friction means lengthwise of said needle-bar and about the longitudinal axis of said needle-bar.

In testimony whereof, I have hereunto

signed my name in the presence of two subscribing witnesses.
